UNITED STATES PATENT OFFICE.

JULIUS PROEGER, OF GREENSBURG, PENNSYLVANIA, ASSIGNOR TO THE HUNTINGTON GLASS COMPANY, OF HUNTINGTON, WEST VIRGINIA.

DESIGN FOR A GLASS VESSEL.

SPECIFICATION forming part of Design No. 22,001, dated November 22, 1892.

Application filed October 28, 1892. Serial No. 450,285. Term of patent 3½ years.

To all whom it may concern:

Be it known that I, JULIUS PROEGER, of Greensburg, in the county of Westmoreland and State of Pennsylvania, have invented a new and original Design for Glass Vessels, of which the following is a full, clear, and exact description, reference being had to the accompanying drawings, forming part of this specification, in which—

10 Figure 1 shows in side elevation a glass vessel ornamented with my design. Fig. 2 is a horizontal section on the line II II of Fig. 1.

My design consists in a vessel having external configuration, substantially as shown 15 in the accompanying drawings and as herein described.

In the drawings, 2 represents the vessel, having oblong paneled portions, each having an inclined or beveled plain face 3 and an oppositely-inclined face 4, having a pattern *in 20 intaglio* or relief.

I claim—

The design for vessels, substantially as herein shown and described.

In testimony whereof I have hereunto set 25 my hand this 10th day of October, A. D. 1892.

JULIUS PROEGER.

Witnesses:

W. B. CORWIN,
THOMAS W. BAKEWELL.
